TAG HOLDER FOR LAUNDRY MARKING MACHINES

Genevieve Petty, Denver, Colo.

Application June 15, 1946, Serial No. 677,049

4 Claims. (Cl. 101—94)

1

This invention relates to a tag holding attachment for laundry marking machines of the type illustrated in United States Patents No. 2,136,461 and 2,157,497, and is designed more particularly as an improvement over the tag holding attachment described and illustrated in applicant's co-pending application, Serial No. 635,841, now abandoned.

In the usual laundry marking machine it is difficult to hold small cloth tags, such as used by dry cleaners, while the customer's mark is being impressed thereon. The principal object of this invention is to provide a highly efficient, easily operated attachment for securely holding a tag in place in the marking machine while the mark is being impressed thereon.

Other objects of the invention are: to so construct the tag holding device that it will not interfere with the normal operation of the marking machine; to provide an attachment which will not be damaged by the rough usage to which such machines are subjected; and to provide an attachment of this character which can be readily applied to the conventional marker without change therein.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a fragmentary side elevation of a typical laundry marking machine with the invention in place thereon;

Fig. 2 is a detail section, taken on the line 2—2, Fig. 1;

Fig. 3 is a similar detail section, taken on the line 3—3, Fig. 2;

Fig. 4 is a fragmentary, detail section, taken on the line 4—4, Fig. 3; and

Fig. 5 is a detail view of a conventional impression pad frame of a typical laundry marking machine illustrating how the invention is applied thereto.

In the drawing, typical parts of a marking machine are designated by numeral as follows: housing 12, type wheels 13, type wheel guards 14, supporting base 15, impression pad 16, impression pad holding frame 34, handle 17, impression arm 18, inking toggle 19, inking toggle

2

bolt 20, inking toggle spring 21, inking pad 22, and inker connecting link 23.

Briefly, the operation of such a marking machine is as follows:

5 The operator sets the type wheels 13 to bring the desired series of letters or numbers into the desired printing alignment on the type wheels. The article to be marked is then placed across the impression pad 16 and the handle 17 is forced 10 forwardly to swing the impression arm 18 toward the type wheels 13.

As the arm moves forwardly, the connecting link 23 pushes the toggle 19 forwardly to bring the ink pad 22 against the aligned type faces.

15 Further movement of the impression arm 18 forces the toggle bolt 20 forwardly, breaking the toggle and allowing the ink pad to swing downwardly from the inked type so that the article on the impression pad 16 can be forced thereagainst. The handle 17 is then swung back to its original position, allowing the spring 21 to straighten the toggle 19 back to the position of Fig. 1.

20 The conventional impression arm 18 is an A-shaped frame having a horizontal cross member 24 adjacent its base. The connecting link 23 is secured between the two sides of the A-shaped frame 18 by means of a horizontal hinge bolt 25.

25 This invention is designed to hold a small cloth tag in place on the impression pad 16 so that it will be securely carried against the type faces on the type wheels 13.

30 The holder employs the hinge bolt 25 for its attachment to the machine. The holder comprises a relatively thin clamping plate 26 having rearwardly turned ears 27 formed on its opposite sides. The ears are perforated for the passage of the bolt 25, and are positioned between the head and nut on the bolt 25 and the side members of the A-shaped frame 18 and project below the handle 17. The projecting extremities of the ears 27 are turned or twisted at right angles to form two flat finger tabs 29.

35 The clamping plate 26 is constantly urged toward the impression pad 16 by means of a single leaf spring 30. One extremity of the spring 30 is riveted, as shown at 31, to the plate 26. The other extremity bears, and is flexed, against the upwardly-turned portion of the L-shaped connecting link 23.

40 The cloth tag, indicated at 32, is clamped between the plate 26 and a flexible backing plate 33. The backing plate is formed from spring brass or bronze, so as to be flexible. It is secured to 45 the impression pad holding frame 34, shown in

detail in Fig. 5, by means of suitable attachment screws 35 which are threaded into suitable screw holes 36 in the frame 34.

The free edges of both the backing plate 33 and the clamping plate 26 are positioned in alignment with and terminate below the impression pad 16. The clamping plate 26 can be lifted from the backing plate 33 to receive the tag 32 by lifting either or both of the finger tabs 29.

Since the latter tabs are positioned immediately below the handle 17, they are within convenient reach of the fingers for lifting purposes.

It will be noted that, as the impression arm 18 swings toward the type wheels, the clamping plate 26 swings to a more perpendicular position. In so doing, it further flexes the leaf spring 30 so that the grip on the tag increases up to the point of final impression. Since the backing plate 33 is flexible, it will act as a cushion to allow the entire structure to recede on contact with the type wheels, to prevent damage.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A tag holding attachment for laundry marking machines of the type having an impression pad carried on an impression arm, and an impression pad frame surrounding said pad, comprising: a backing plate secured to said frame below said pad and extending upwardly so that its upper edge terminates immediately below said pad; a horizontal hinge pin extending across said frame below said pad; a relatively thin clamping plate; ears formed on the extremities of said plate and turned at right angles to the plane thereof, said ears being perforated to receive said hinge pin, the upper extremity of said clamping plate terminating immediately below the impression pad in alignment with said backing plate immediately below said impression pad; and means for urging said clamping plate toward said backing plate to clamp the lower edge of a laundry tag between the two plates so that it will extend upwardly over the pad.

2. A tag holding attachment for laundry marking machines of the type having an impression pad carried on an impression arm, with an impression pad frame surrounding said pad, the arm being connected by means of an L-shaped connecting link with an inking arm, the connecting link and the impression arm being connected together by means of a hinge pin, comprising: a relatively thin clamping plate; ears formed on the extremities of said plate and turned at right angles to the plane thereof, said ears being perforated to receive said hinge pin, the upper extremity of said clamping plate ter-

minating immediately below the impression pad; a backing plate secured to said frame below said pad and extending upwardly to a termination immediately below said impression pad; and a leaf spring secured to said clamping plate and extending downwardly into contact with said connecting link and urging said clamping plate to clamp the lower edge of a laundry tag between the two plates and over said impression pad toward said backing plate.

3. A tag holding attachment for laundry marking machines of the type having an impression pad mounted in a pad frame carried on an impression arm, the arm being connected by means of an L-shaped connecting link with an inking arm, the connecting link and the impression arm being connected together by means of a hinge pin, comprising: a relatively thin clamping plate; ears formed on the extremities of said plate and turned at right angles to the plane thereof, said ears being perforated to receive said hinge pin, the upper extremity of said plate terminating below the impression pad; a backing plate secured to said pad frame and terminating below said impression pad; a leaf spring secured to said clamping plate and extending downwardly into contact with said connecting link and urging said clamping plate toward said backing plate; and finger tabs formed on and projecting from said ears, whereby the clamping plate may be lifted from the backing plate against the action of said spring.

4. A tag holding attachment for laundry marking machines of the type having an impression pad carried in an impression pad frame on the upper extremity of an impression arm comprising: a backing plate secured to said frame below said pad and extending upwardly so that its upper edge terminates immediately below said pad; a relatively thin clamping plate hingedly mounted on said impression arm below a backing plate, said pad with its upper edge in alignment with the upper edge of said backing plate; spring means urging said clamping plate toward said backing plate to clamp the lower edge of a laundry tag between the two plates and over the pad; and finger engaging means projecting from said clamping plate for moving the latter against the action of said spring means.
